UNITED STATES PATENT OFFICE.

ELMER E. LANE, OF SOUTH BERWICK, MAINE, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-BLANK-SKIVING MACHINE.

1,382,656.

Specification of Letters Patent. Patented June 28, 1921.

Application filed July 18, 1917, Serial No. 181,445. Renewed July 30, 1918. Serial No. 314,270.

To all whom it may concern:

Be it known that I, ELMER E. LANE, a citizen of the United States, residing at South Berwick, in the county of York and State of Maine, have invented certain new and useful Improvements in Shoe-Blank-Skiving Machines; and I do hereby declare the following to be a full, clear, and exact description of the invention, such as will enable others skilled in the art to which it appertains to make and use the same.

This invention relates to shoe blank skiving machines, and more particularly to a machine for shanking out or for evening and shanking out shoe soles.

The object of the invention is to provide a skiving machine of improved construction and mode of operation by which a predetermined portion of a blank may be accurately skived.

With this object in view one feature of the invention contemplates the provision in a skiving machine having a skiving knife, a pressure roll, a die roll, means to rotate the rolls continuously, and means to advance blanks to the rolls, of a matrix movably mounted on the die roll and means to control the movement of the matrix to bring it into position to operate upon a predetermined portion of the blank. In the preferred form of the invention a pair of matrices is employed for positioning opposite sides of the shank portion of the sole to be skived, and these matrices are secured to sleeves which are rotatably mounted on and driven independently of the die roll. The die and pressure rolls rotate continuously and the matrix driving mechanism is arranged to set the matrices into operation to bring them into position on the shank portion of the sole as the sole is advanced between the rolls. The diameter of the die and pressure rolls is small to permit the cutting edge of the skiving knife to be positioned close to the line of centers of the rolls, so that the die roll makes two revolutions while the sole is being treated and the matrix makes one revolution and is stopped in a position ready to operate on the succeeding sole.

Another feature of the invention contemplates the provision in a skiving machine having a skiving knife, a pressure roll, a die roll, and means to rotate the rolls, of a

matrix mounted on the die roll and mechanism for driving the matrix having provision for adjustment whereby the position of engagement of the matrix with the sole may be varied for treating different kinds of soles.

Another feature of the invention contemplates the provision in a skiving machine having a skiving knife and a pressure roll, of a die roll having a uniform diameter, means for rotating the rolls to advance a sole across the skiving knife, and a matrix movably mounted on the die roll to coöperate with the die roll in positioning a sole, whereby the sole will be skived and evened simultaneously as it is advanced across the skiving knife.

Another feature of the invention contemplates the provision in a skiving machine having a skiving knife and a die roll, of a pressure roll shaft having a series of toothed feeding disks mounted for movement transversely of said shaft, and means for independently driving each disk.

Another feature of the invention contemplates the provision in a skiving machine having a skiving knife and a die roll, of a feed roll provided with a series of teeth on its periphery, a portion only of the crown of each of said teeth being pointed, and means for driving the die and pressure rolls to advance the blank across the skiving knife.

A further feature of the invention contemplates the provision in a skiving machine having a skiving knife, a pressure roll, a die roll and a feed table for supporting blanks, of a series of perforations in said table, means for creating a suction through said perforations to flatten a blank on the table, and means for advancing the blank across the table to the rolls.

A further feature of the invention contemplates the provision in a skiving machine having a skiving knife, pressure and die rolls, and a feed table for supporting blanks in stacked formation, of means for simultaneously feeding right and left soles to the rolls, and means for supporting blanks in separate stacks on the table comprising adjustable side plates for transversely positioning the blanks in the stacks, and a pressure plate for each stack to force the blanks down against the table.

Other features of the invention consist in certain improved features of construction and combination of parts, the advantages of which will be obvious to those skilled in the art from the following description.

The various features of the invention are illustrated in the accompanying drawings, in which Figure 1 is a view in side elevation of the upper portion of a skiving machine embodying the preferred form of the invention; Fig. 2 is a front elevation of the machine illustrated in Fig. 1; Fig. 3 is a top plan view, partly in section, of the machine showing the feed table and die roll; Fig. 4 is a detail vertical sectional view, taken on the line 4—4 of Fig. 3; Fig. 5 is a vertical sectional view of the pressure and die rolls taken on the line 5—5 of Fig. 4; Fig. 6 is a detail view of the mutilated gears 20 for driving the matrix; Fig. 7 is a plan view of the machine, partly in section, on the line 7—7 of Fig. 1, showing the blank magazine and the follower for holding the blanks in stack formation; Fig. 8 is an enlarged 25 detail view showing a portion of a feeding disk of the pressure roll; and Fig. 9 is a detail sectional view taken on the line 9—9 of Fig. 8.

The machine illustrated in the drawings is 30 adapted to even outsole blanks and skive them in the shank portion. The blanks are positioned in a magazine in two stacks, one stack being right soles and the other stack being left soles, and each stack is pressed down 35 upon a feed table by a follower. Blanks from both stacks are advanced simultaneously to the bite of a die roll and a co-operating pressure roll by means of a reciprocating feed slide. The blanks are held 40 upon the die roll by the pressure roll in position for the skiving and evening operations, and the rotation of the rolls serves to advance the blanks across a skiving knife, the cutting edge of which is located between 45 the rolls at substantially their line of centers. As the soles are advanced against the skiving knife, the portions lying between the toe ends and the ball lines are positioned by the die roll so that they are evened. 50 At the time the ball lines reach the skiving knife two sets of matrix projections, shaped to form the skivings at each side of the shanks of the soles, come into contact with the soles, and as the soles are advanced 55 from the ball lines to the breast lines each side of the shanks is skived and the central portions of the soles between the skivings are evened. The matrix projections pass off of the soles at the breast lines, and 60 the heel seats of the soles are positioned by the die roll to be evened. The die and pressure rolls are continuously rotated and make two revolutions while operating upon a blank. The matrix projections are operated 65 to come into position upon the shank portion

of the sole, make one revolution and stop ready for the next skiving operation, while the die and pressure rolls complete the second revolution.

The die roll (Figs. 4 and 5) comprises a 70 shaft 12 upon which is fixed an evening cylinder 14. The shaft 12 is journaled in bearings 16 and 18 formed on the opposite sides of the machine frame, and has a threaded connection in the bearing 16 with 75 a driving gear 20 from which the shaft may be disconnected to be removed from the bearings. The evening cylinder 14 has a uniform diameter and is arranged to position 80 a sole with reference to the skiving knife so that the sole will be skived to a uniform thickness throughout its length.

To position the soles so that they may be shanked out, two sets of matrix projections 22 and 24 (Figs. 4 and 5) are rotatably mounted on the face of the evening cylinder 14, the set of matrix projections 22 being constructed for operating on right soles and the set of matrix projections 24 being constructed for operating upon left soles. The matrix projections are shaped to conform to the convex surface of the evening cylinder and are attached to sleeves 26, 28 and 30 which are rotatably mounted in grooves formed on the face of the evening cylinder. 95 To permit the sleeve 28 to be placed in the groove at the center of the evening cylinder, a portion of the cylinder between the sleeves 28 and 30 is made in the form of a removable sleeve 31. The matrix projections 22 and 24 for operating upon the inside shanks of the right and left soles (Fig. 3) are secured to the sleeves 26 and 30 respectively, and the matrix projections 22 and 24 for operating upon the outside shanks of 105 the right and left soles are both connected to the central sleeve 28. To rotate the matrix projections in unison to simultaneously bring them into operation upon right and left soles, gears 32 are formed on the faces 110 of the sleeves 26, 28 and 30 and mesh with gears 34 pinned to a shaft 36 which is journaled between opposite sides of the machine frame.

The matrix projections are intermittently 115 rotated to bring them into position upon the shank portion of the sole. The intermittent driving mechanism (Figs. 3 and 6) comprises a mutilated gear 38 loosely mounted on a sleeve 40 in the bearing 18, and a 120 mutilated gear 42 which is keyed to a sleeve 44 loosely mounted in a bearing 46 formed in the right-hand side of the machine frame (Fig. 3). The gear 38 is locked to the matrix sleeve 30 so that a 125 rotation of the gear 38 will impart a simultaneous movement to the matrix sleeves through the gears 32 and 34. The mutilated gear 42 serves as a driving gear and has sufficient teeth on its periphery to im- 130

part a complete revolution to the gear 38. When the gear 38 has completed a revolution, an untoothed section 48 on the gear 42 comes into contact with an untoothed section 50 on the gear 38 and locks the gear 38 from rotation until the section 48 has been moved across the section 50 and the teeth on the gear 42 come into contact with the gear 38 to release it for rotation. The gear 42 is continuously driven at a proper speed to rotate the gear 38 at the same speed as the speed of rotation of the evening cylinder 14. The gear 42 makes one revolution while the evening cylinder makes two revolutions so that the gear 38 will make one revolution in unison with the evening cylinder and will be stopped from rotation during the next revolution of the evening cylinder.

The pressure or feed roll (Figs. 4 and 5) comprises a series of feeding disks 52 which are loosely mounted on a shaft 54 fixed between opposite sides of the machine frame. Each of the feeding disks has a central opening of larger diameter than the diameter of the shaft 54, which permits the disk to move transversely of the shaft. To hold the feeding disks in pressure position upon the work, a series of gear teeth 56 are formed around the periphery of the disks and the disks articulate with a series of driving gears 58 mounted in front of the feed roll, a series of alining gears 60 mounted at the rear of the feed roll, and a series of pressure gears 62 mounted above the feed roll. The driving gears 58 (Fig. 4) are keyed to a driving shaft 64 which is journaled between opposite sides of the machine frame, and the alining gears 60 are loosely mounted on a shaft 66 which is fixed between opposite sides of the machine frame. The pressure gears 62 are rotatably mounted between arms 68 (Fig. 4) projecting downwardly from leaf springs 70 which are supported at their ends by the arms of a yoke 72. The yoke 72 extends across the pressure roll and is mounted on a pair of rods 74 and 75 which extend between plates 76 at opposite sides of a magazine supporting frame. The ends of the rod 74 are adjustable in slots 80 formed in the plates 76 so that the yoke 72 may be adjusted to move the pressure gears 62 toward and from the feeding disks, whereby the pressure of the feeding disks upon the sole may be varied. The pressures of the individual feeding disks which engage the different portions of the sole to position it on the matrices may be regulated also by using leaf springs 70 for pressing on these disks, which have a definite strength or stiffness determined by the pressure required to shape the sole upon the matrices. When the feeding disks yield upon the work, they are constrained to move vertically or sub-

stantially in the line of centers of the die and feed rolls by the gears 58 and 60, and the shaft 54 will not permit the disks to be moved out of mesh with the gears. To assist the feeding disks in positioning a blank on the die roll, a series of resilient stripping fingers 82 are supported at the rear of the feed roll and extend between the feeding disks. The stripping fingers are adjustably mounted on a rod 83 which extends across the feed roll and is supported at its ends in the plates 76.

When the machine is in operation, the die and pressure rolls are rotated continuously. To drive the die and pressure rolls, the gear 20 on the die roll shaft (Figs. 1, 2 and 7) meshes with an intermediate gear 84 loosely mounted on a shaft 86 (Fig. 3) which extends through the sleeve 44 in the bearing 46. The gear 84 meshes with a gear 87 fixed on the feed roll driving shaft 64, and a second gear 88 fixed on the shaft 64 meshes with a gear 90 fixed on the main driving shaft 92. The shaft 92 is provided with loose and tight pulleys and can be started and stopped at the will of the operator. To drive the gears 38 and 42 which operate the matrix projections, a timing gear 94 (Fig. 3) is loosely mounted on the shaft 86 and is connected, by means of a collar 96, with the sleeve 44 upon which the mutilated gear 42 is keyed. The gear 94 meshes with a gear 98 which is loosely mounted on a stud shaft 100 projecting out from the right-hand side of the machine frame (Fig. 3). The hub of the gear 98 is arranged to have an interlocking connection with the hub of a gear 102 which is loosely mounted on the shaft 100 and meshes with a gear 106 fixed on the end of a feed slide driving shaft 108 journaled between opposite sides of the machine frame. A gear 110 is fixed to the end of the shaft 108 opposite the gear 106 and meshes with an intermediate gear 112 which, in turn, meshes with the gear 84. The gear 112 is loosely mounted on a stud shaft 116 which is secured in an arm 118 formed on the machine frame.

Since the length of the shank varies in soles of different sizes and styles of shoes, different matrix projections are employed for shanking out these soles. The time of rotation of each of the different kind of matrix projections must be corrected, with relation to the rotation of the die and feed rolls, so that the matrix projections will register with the shank portion of the sole. To vary the time of rotation of the matrix projections, the connection of the timing gear 94 with the collar 96 (Figs. 1 and 3) consists of a pair of bolts 120 passing through slots 122 in the gear 94 and secured in the collar 96, which permits the gear to be adjusted circumferentially on the collar. When the bolts 120 are loosened, the driving

gears may be rotated by a hand wheel 124 (Fig. 2), while the timing gear stands at rest, and when the die roll is brought into the proper position, relatively to the matrix 5 projections, to have the matrices register with the shank portion of a sole, the bolts will be tightened to set the machine ready for operation.

In addition to pressing a blank against 10 the die roll, the teeth of the feeding disks on the pressure roll grip the blank and feed it against the skiving knife. Heretofore trouble has been experienced with toothed feed rolls in that the teeth of the feed roll at 15 the portion of greatest pressure would penetrate too deeply into the blank and injure it. To avoid mutilation of the blanks, about one-half of the crown of each gear tooth 56 on the feeding disks is extended to form a 20 sharp feeding point 126 (Figs. 8 and 9), and the other half of the crown is flat to serve as a stop for limiting the penetration of the point 126 into the blank. The penetration of the points 126 is sufficient to give a good 25 grip on the stock to insure a positive feed of the blank. The teeth on the gears 58, 60 and 62 which mesh with the teeth 56 on the feeding disks, are specially constructed to provide for the extra length of the feeding 30 points 126 on the teeth 56.

The skiving knife indicated at 128 (Fig. 4) is adjustably clamped upon the upper face of a knife carrier 130 which is held in position upon the machine frame by bolts 35 132 which pass through slots 134 formed at each side of the carrier and are threaded into the machine frame. To the lower portion of the carrier is connected a pair of links 136 (Fig. 5) which are loosely mounted upon a 40 rod 138 journaled between opposite sides of the machine frame. The mounting of the rod 138 in the links 136 is eccentric to the mounting of the rod in the machine frame, and a square shank 140 formed on 45 the right-hand end of the rod (Fig. 5) is adapted to receive a wrench by which the rod may be rotated to vertically adjust the carrier. The slots 134 permit the adjustment of the carrier, and the carrier is locked 50 in its adjusted position by the bolts 132. With the above construction the bolts 132 may be removed, and by rotating the carrier upon the links 136 the knife may be withdrawn from between the die and pressure 55 rolls while it is attached to the carrier, to permit the knife to be removed, sharpened and replaced between the rolls without requiring a readjustment of the knife with reference to the die roll. During the skiving 60 operation the blanks pass out between the knife and die roll and the waste scrap is discharged above the knife. To prevent the waste from being mingled with the blanks a chute 142 (Figs. 1, 2 and 7) is attached to 65 the rear of the knife carrier 130 to conduct

the waste out to a point where it may be separately collected.

The sole blanks to be skived are arranged in a magazine in two stacks, one stack being right soles and the other stack being left soles. The magazine comprises a feed table 144 for supporting the soles, a front wall 146 for longitudinally positioning the soles, a pair of side gages 148 for transversely positioning the toe ends of the soles, and a 70 pair of side gages 150 for transversely positioning the heel ends of the soles. The feed table 144 has its upper face approximately on a level with the upper side of the die roll and constitutes the upper side of a 80 closed air-box 152 which is formed on the machine frame directly behind the die and pressure rolls. The front wall 146 is a wall having a plane surface which extends between side plates 76 of the magazine supporting frame. The lower portion of the front wall 146 is an adjustable gate 156 which has its bottom edge supported above the face of the feed table a distance slightly greater than the thickness of a sole, and acts 85 as a separator to prevent more than one sole of each stack from being advanced to the die and feed rolls at a time. A guide 158 is attached to the lower edge of the gate and projects toward the die roll to assist in flattening the blanks as they are advanced to the die and pressure rolls. To adjust the gate 156 for separating blanks of different thicknesses, a hook 160 is secured to the center of the rear face of the gate and is 90 engaged by a lug 162 secured to a rod 164 journaled between plates 76. A square shank 166 is formed on the right-hand end of the rod 164 (Figs. 1 and 2) which is 95 adapted to receive a wrench by which the rod may be rotated to raise and lower the gate 156. The bearing of the rod adjacent the shank 166 is split and is provided with a clamping bolt 168 by which the rod may be locked to hold the gate in any desired 100 position. The side gages 148 (Figs. 1, 2, 3 and 4) consist of plates for engaging the inside foreparts of the soles and are adjustable along the front wall 146. To hold the gage plates in position, rods 170 mounted in 105 carriers 172 are secured in lugs 174 formed on the outer face of the gage plates 148. The carriers 172 are slidably mounted on a horizontal rod 176 connected between the plates 76 to allow the side gages 148 to be 110 adjusted transversely of the feed table. The heel positioning gages 150 consist of plates 115 adjustably secured to brackets 178 which are adjustable both longitudinally and transversely of the feed table. With the adjustable side gages 148 and 150 the transverse position of the sole on the feed table may be varied to bring the sole into transverse alignment with the matrix projections, and the angular position of the sole with relation 120 to

to the line of feed may be varied to have the ball line of the sole register with the leading edges of the matrix projections.

To assist in holding the stacks of blanks 5 in position against the feed table, presser plates 180 (Figs. 1, 2 and 7) are arranged to rest upon the top of each stack of blanks and are positively forced downwardly to flatten the blanks on the table. The presser 10 plates are attached to followers 182 which are secured to the lower end of vertically movable rods 184. The rods 184 are slidably mounted in a bracket 186 projecting forwardly from the upper end of the front wall 15 146. A rack 188 is formed on the side of each of the rods 184 which articulates with gears 190 (Fig. 1) fixed on a shaft 192 journaled in the bracket 186. The shaft 192 is provided with a beveled gear 194 which 20 meshes with beveled gears 196 and 198 loosely mounted on a driving shaft 200, which is journaled at the top of the magazine supporting frame between the side plates 76. The shaft 200 is arranged to be 25 operated to yieldingly hold the presser plates on the top of the stacks and move the plates downwardly in the magazine as the blanks are skived. The shaft is stopped when the soles in the stacks have reached a 30 predetermined level and the direction of rotation automatically reversed to move the presser plates upwardly to permit new stacks of blanks to be placed in the magazine. After the magazine has been filled, 35 the shaft 200 is arranged to be set into operation through a foot treadle to force the new stacks of blanks down upon the feed table. The mechanism for carrying out these operations is substantially the same as 40 that shown and described in the patent to Scott No. 969,987 dated September 13, 1910, and since it does not form a part of this invention it is not described in detail herein. The followers 182 are provided with a series 45 of slots 202 by which the pressure plates 180 may be transversely adjusted for operating on different styles and sizes of sole blanks.

To assist in flattening the blanks upon the feed table, a series of perforations 204 50 are formed in the upper face of the table and a strong suction is maintained through the perforations. The perforations 204 are arranged to correspond approximately to the outline of the sole in order that the entire 55 surface of the sole may come under the action of the suction. To provide for feeding different styles and sizes of blanks, plates having different forms of perforations may be used on the feed table. To secure an effective suction the air-box 152 (Figs. 1 and 2) under the feed table 144 has a tube 206 secured to its bottom wall which is arranged to be connected with an exhaust fan 208 mounted on the base of the machine 60 frame, or with an air suction tube which is

commonly used in shoe factories. The suction acts on the blank while it is traveling across the table so that it will be held in flat position to pass under the gate 156. The blanks are automatically advanced from the 70 magazine to the die and pressure rolls by a pusher plate or feed slide 210 which is slidably mounted on the top of the feed table 144. A pair of rounded slots 212 (Figs. 3 and 7) are formed in the leading edge of the 75 feed slide and project around a considerable portion of the heel end of the soles to hold them in transverse alinement as they are advanced to the die roll. The feed slide 210 is attached to a slide block 214 (Figs. 1 and 2) 80 which is slidably mounted in guides formed in the table 144. A link 216 pivoted to the lower face of the slide block 214 is connected to the upper end of a lever 218 which is pinned to a rock shaft 220 journaled in bearings in the air-box 152. The shaft extends outside of the air-box, and on its outer end is secured a cam lever 224 which carries a cam roll 226 arranged to project into a closed cam path formed in the side of a cam 85 228. The cam 228 is loosely mounted on the feed slide driving shaft 108 and is arranged to be connected with the shaft by means of a clutch 230 (Fig. 2) which is slidably splined on the shaft. To shift the clutch 230 into 90 and out of connection with the cam 226, a bellcrank lever 232, pivoted at the side of the air-box 152, has one arm connected with the clutch 230 and the other arm connected with a rod 234 which is operated by a foot treadle, 100 not shown. The clutch 230 can only be connected with the cam 226 at a position of the shaft 108 in which the cam will be rotated in timed relation to the rotation of the matrix projections, to insure that the matrix 105 projections will register with the shank portions of soles advanced by the feed slide.

If at any time it is desired to use the machine for evening soles without skiving the shank portions, the gear 98 may be readily 110 removed so that the mutilated gear 42 will not be driven. When the gear 42 is idle the mutilated gear 38 will be locked from rotation and hold the matrix projections in such a position that they will not interfere with 115 the sole evening operation.

While the machine is well adapted for simultaneously shanking out and evening soles, it will operate with equal facility for shanking out soles which have been 120 previously evened. Further, certain features of the invention are not limited to the use in machines for shanking out or evening shoe soles, but may be used in many other relations.

The operation of the machine has been described in connection with the specific construction of the parts of the machine, and further description of the operation is believed to be unnecessary.

The preferred form of the invention having been thus described, what is claimed as new, is:

1. A shoe blank skiving machine, having, in combination, a skiving knife, a die roll, a pressure roll, a matrix rotatably mounted on the die roll, means for rotating the rolls, and independent mechanism for rotating the matrix at the same speed as the die roll, 5
10. 2. A shoe blank skiving machine, having, in combination, a skiving knife, a die roll, a pressure roll, means for continuously driving the rolls during the passage of a blank therebetween for its entire length, a matrix rotatably mounted on the die roll, and means for relatively rotating the matrix and die roll, 15
15. 3. A shoe blank skiving machine, having, in combination, a skiving knife, a pressure roll, a die roll, a sleeve provided with a matrix rotatably mounted on the die roll, means to rotate the rolls continuously during the passage of a blank therebetween for its entire length, and additional means for 20 rotating the sleeve, 25
20. 4. A shoe blank skiving machine, having, in combination, a skiving knife, a pressure roll, a die roll, a matrix for operating on a portion of the length of the blank, said matrix being mounted on the die roll, means for rotating the rolls, and means to rotate the matrix only when a predetermined portion of a blank is being operated upon, 30
25. 5. A shoe blank skiving machine, having, in combination, a skiving knife, a pressure roll, a die roll, a matrix rotatably mounted on the die roll, means to drive the rolls continuously during the passage of a blank 35 therebetween for its entire length, and means to rotate the matrix intermittently, 40
30. 6. A shoe blank skiving machine, having, in combination, a skiving knife, a pressure roll, a die roll, means to rotate the rolls continuously, means to advance blanks to the rolls, a matrix movably mounted on the die roll, and means to control the movement of the matrix to bring it into position to operate on a predetermined portion of the blank, 45
35. 7. A shoe blank skiving machine, having, in combination, a skiving knife, a pressure roll, a die roll, a matrix movably mounted on the die roll and arranged to operate on a portion of a blank intermediate its ends, means to rotate the rolls continuously during the passage of a blank therebetween for its entire length, and means to move the matrix relatively to the die roll to bring the matrix into operation on a predetermined portion 50 of the blank intermediate its ends, 55
40. 8. A shoe blank skiving machine, having, in combination, a skiving knife, a pressure roll, a die roll, a matrix rotatably mounted on the surface of the die roll, and arranged 60 to operate on a portion of a blank intermediate its ends, 65
45. 9. A shoe blank skiving machine, having, in combination, a skiving knife, a pressure roll, a die roll having a matrix rotatably mounted on its surface, means to rotate the rolls continuously, means to advance blanks to the rolls intermittently, means to rotate the matrix on the die roll intermittently, and means to vary the time of operation of the matrix relatively to the operation of the rolls, 70
50. 10. A shoe blank skiving machine, having, in combination, a die roll, a pressure roll, a skiving knife, means for driving the rolls continuously, a matrix mounted on the die roll, means for relatively rotating the matrix and die roll, and mechanism for feeding blanks to the rolls in timed relation to the operation of the matrix, 75
55. 11. A sole skiving machine, having, in combination, a die roll, a pressure roll, a skiving knife, means to operate the rolls, a matrix rotatably mounted on the die roll, and an independent driving mechanism constructed and arranged to control the operation of the matrix to bring the matrix into position to operate upon the shank portion of the sole, 80
60. 12. A sole skiving machine, having, in combination, a die roll, a pressure roll, a skiving knife, means to operate the rolls, a matrix movably mounted on the die roll, and mechanism for driving the matrix having provision for adjustment whereby the position of engagement of the matrix with the sole may be varied for skiving different kinds of soles, 85
65. 13. A sole skiving machine, having, in combination, a skiving knife, a pressure roll, a die roll having a uniform diameter for evening soles, means for rotating the rolls, and a matrix movably mounted on the die roll to coöperate with the die roll to position a sole to be skived and evened simultaneously as it is advanced across the skiving knife, 90
70. 14. A shoe blank skiving machine, having, in combination, a die roll, a skiving knife, a pressure roll shaft, a series of toothed feeding disks mounted for movement transversely of said shaft, and means for independently driving each disk, 95
75. 15. A skiving machine, having, in combination a skiving knife, a die roll, a pressure roll shaft, a hollow pressure roll yieldingly mounted for transverse movement on said shaft, peripheral teeth on said pressure roll, a plurality of gears meshing with the teeth on the pressure roll and arranged about the 100

roll to hold it in position upon the work, and means for driving the rolls.

16. A skiving machine, having, in combination, a skiving knife, a die roll, a pressure roll shaft, a hollow pressure roll mounted for movement transversely on said shaft, peripheral teeth on said pressure roll, a plurality of gears arranged around the pressure roll in mesh with its teeth, one of said gears being positively driven to drive the pressure roll, and yielding means operating upon another of said gears to press the roll against the work.

17. A skiving machine, having, in combination, a skiving knife, a die roll, a pressure roll shaft, a plurality of toothed feeding disks mounted on the shaft, a plurality of sets of gears arranged around the feeding disks with one gear of each set in mesh with each feeding disk, one set of said gears being positively driven to drive the disks and springs supporting another set of said gears to press the disks against the work.

18. A skiving machine, having, in combination, a skiving knife, a die roll, a pressure roll shaft, a plurality of toothed disks mounted for transverse movement on said shaft, a plurality of gears in mesh with each disk and arranged around its periphery, means for driving the disk, and a spring operating upon each disk to press it against the work.

19. A skiving machine, having, in combination, a skiving knife, a die roll, a feed roll provided with a series of teeth on its periphery, each of said teeth having only a portion of its crown pointed, and means for driving the rolls.

20. A skiving machine, having, in combination, a skiving knife, a die roll, a feed roll provided with a series of teeth on its periphery, each of said teeth having only a portion of its crown pointed, means for yieldingly forcing the feed roll against the work, and means for driving the rolls.

21. A skiving machine, having, in combination, a skiving knife, a die roll, a pressure roll having teeth around its periphery, part of the crown of each tooth being extended to form a sharp point, and the other part being flat to form a stop to limit the penetration of the point into a blank, and means for driving the rolls.

22. A skiving machine, having, in combination, a skiving knife, a die roll, a pressure roll shaft, a pressure roll consisting of a plurality of disks mounted on said pressure roll shaft, the periphery of each disk being provided with teeth, the crown of each tooth having a point and a flat face, and means for driving the rolls.

23. A skiving machine, having, in combination, a skiving knife, a die roll, a pressure roll shaft, a pressure roll consisting of a plurality of disks mounted on said pressure

roll shaft, the periphery of each disk being provided with gear teeth, a portion of the crown of each of said gear teeth being pointed, a driving gear in mesh with each disk, and means for operating the driving gear and the die roll.

24. A skiving machine, having, in combination, a die roll and a pressure roll arranged with their peripheries in close proximity, a skiving knife having its cutting edge projecting in between the rolls, and a knife carrier on which the knife may be clamped in adjusted position, said carrier being constructed and arranged to be bodily moved so that the knife while on the carrier may be withdrawn from and inserted between the rolls without requiring a readjustment.

25. A skiving machine, having, in combination, a die roll and a pressure roll arranged with their peripheries in close proximity, a skiving knife having its cutting edge projecting in between the rolls and a knife carrier on which the knife may be clamped in any adjusted position, the upper part of said carrier being arranged to be bolted to the machine frame, and the lower part of the carrier having a linked connection with the frame whereby the knife may be withdrawn from and inserted between the rolls while attached to the carrier.

26. A sole skiving machine, having, in combination, a skiving knife, pressure and die rolls, a feed table, means for simultaneously feeding right and left shoe soles to the rolls, and means for supporting the right and left soles in separate stacks on the table comprising adjustable side plates for transversely positioning the soles in the stacks, and a pressure plate for each stack to hold the soles down upon the table.

27. A sole skiving machine, having, in combination, a die roll, a pressure roll, a skiving knife, a feeding table, means for feeding blanks from the table to the rolls, and means for supporting blanks in a plurality of stacks upon the table in position to be operated upon by the feeding means comprising side gages for determining the transverse position of the stack, a pressure plate for holding each stack pressed upon the table, a pair of followers for supporting the pressure plates, and means by which the presser plates may be adjusted transversely of the followers to provide for different sizes of blanks.

28. A skiving machine, having, in combination, a skiving knife, a die roll, a pressure roll, a feed table, a magazine for separately positioning right and left soles in stack formation upon the table, means for continuously rotating the rolls, and means operating in timed relation to the rotation of the rolls for simultaneously advancing a blank from each stack to the rolls.

29. A skiving machine, having, in combi-

nation, a die roll, a pressure roll, a skiving knife, a feed table provided with a series of perforations, means for creating a suction through said perforations to flatten a blank 5 on said table, and means for advancing the blank across said table to the rolls.

30. A skiving machine, having, in combination, a die roll, a pressure roll, a skiving knife, a feed table provided with a series of 10 perforations, means for advancing blanks across the table to the rolls, and means to position blanks on the table above said perforations, comprising side gages for determining the transverse position on the table, 15 and means to create a suction through said perforations to hold the blank in position while it is being advanced to the rolls.

31. A skiving machine, having, in combination, a die roll, a pressure roll, a skiving 20 knife, a perforated feed table, means for transversely positioning a plurality of blanks arranged in stack formation above the perforations in the table, means for engaging the ends of the blanks to longitudinally position them and advance them to the rolls, 25 and means to create a suction through the said perforations to flatten the bottom blank of the stack on the table and to draw the next to the bottom blank down on the table 30 after the bottom blank has been advanced to the rolls.

32. A sole skiving machine, having, in

combination, a die roll, a pressure roll, a skiving knife, a perforated feed table, side gages for transversely positioning a plurality of blanks arranged in stack formation 35 above the perforations in the table, a pusher plate for advancing blanks from the bottom of the stack to the rolls, means to create a suction through said perforations to flatten 40 the bottom blank on the table, and a presser plate acting on the stack of blanks to press the stack down on the table.

33. A shoe blank skiving machine having, in combination, blank feeding and skiving 45 devices including a skiving knife, a die roll less in circumference than the length of the blank to be operated upon and a pressure roll past which the blank is fed for its entire length, a matrix rotatably mounted on the 50 die roll, and means for causing the matrix to act upon a predetermined portion of the blank.

34. A shoe blank skiving machine having, in combination, blank feeding and skiving 55 devices including a skiving knife, a die roll less in circumference than the length of the blank to be operated upon and a pressure roll past which the blank is fed for its entire length, a matrix rotatably mounted on the 60 die roll, and means for rotating the matrix once only during the passage of the blanks between the rolls.

ELMER E. LANE.
